SWEAT BAND

John Cavanagh, East Norwalk, Conn., assignor
to Hat Corporation of America, Norwalk,
Conn., a corporation of Delaware

Application August 23, 1935, Serial No. 37,546

7 Claims. (Cl. 2—181)

The present invention relates to improvements in sweat bands for hats and caps. In particular it relates to fabric sweat bands rather than the usual leather bands, and to composite rather than single ply bands.

A fabric sweat band has the desirable characteristic of being more flexible and of more readily absorbing perspiration than a leather band, and of providing a smooth and silky feel and a better and more comfortable conforming shape, especially at the forehead. A fabric sweat band also provides a large number of interstices between the woven fibres whereby air may pass between the wearer's forehead and the cloth band more freely than with leather bands, thereby providing freer circulation at the point where the sweat band engages the forehead and serving to make the wearer feel more comfortable.

However, with most of the fabric sweat bands heretofore provided there was a disadvantage of the perspiration permeating the sweat band and passing to the hat, and in some cases through the hat to the outer hat band itself. Because a fabric sweat band is preferably soft and yielding there is a possibility of wrinkling and a problem of supporting it in an inverted position within the crown of a hat.

It is an object of the present invention to provide a fabric sweat band adapted to absorb perspiration much more readily than leather and other sweat bands heretofore provided.

To this end the present invention provides a fabric sweat band of materials readily adapted to absorb the perspiration and which is constructed in a novel manner to prevent the perspiration from seeping entirely through the fabric head cloth to the hat body or outer hat band which would therefore spoil or mar the appearance of the hat.

An especially important feature of the present invention in this connection, is the provision of a composite sweat band for hats and caps which is provided with a fabric head band imparting a smooth fit and feel at the wearer's head and which is provided with an absorbent backing member, having a high capacity of absorption and subsequent evaporation.

A complementary feature in connection with this form of the invention is the provision of a water-proof coating directly upon the absorbent backing member adapted to prevent the body acids, perspiration and the like in the absorbent member from seeping therethrough to the hat body and to the hat band. Thus, it is apparent that the present invention provides an economical

fabric sweat band adapted to absorb a large amount of perspiration, yet adapted to prevent the absorbed perspiration from seeping through to the hat body where it would mar the general appearance of the hat.

Another feature of the invention is the provision of a separate barrier or water-proofing member in back of the absorbent backing member, serving mainly as a dam, thereby providing a three-ply composite sweat which is both highly absorbent and highly water-proof or moisture impervious.

In light colored hats especially, and in warm climates, it is always a very real problem to keep the perspiration from seeping through a sweat band and marring the appearance of a hat and outer band.

It is an object of the present invention to provide a sweat band which is unusually effective in preventing the hat body and outer hat band from being spoiled by moisture and perspiration, and to provide such improved sweat bands which will be applicable to all styles of hats and caps.

Although fabric sweat bands for hats are desirable from the standpoint of smooth fit and feel, air spaces to insure a more comfortable and more natural engagement and condition of the forehead, as hereinbefore set forth, these desirable objects are impeded sometimes by the soft fabric of the hat band itself when it wrinkles or is not properly supported within the hat.

It is another object of the present invention to provide a fabric sweat band having all the aforesaid characteristics, but which will always be smooth and properly supported within the hat.

To this end, the present invention provides a novel structure for imparting and maintaining the fabric sweat band in a neat, smooth general appearance at all times and so arranged that it will be properly supported at all times and will not be pulled from within the crown.

Another object is to provide a fabric sweat band which may be made in various forms, for example with a flange extending under the brim section of a hat a considerable extent in order to prevent perspiration from getting around the lower end thereof and seeping into the brim of the hat.

Accordingly, an important feature of the present invention is the provision of a novel backing member adapted to be preformed with a considerable flange and to support a fabric thereover, or to take a fabric in its original flat form and be formed with a flange in such a manner as to support the fabric under the rim of the hat.

considerable extent and thereby impart a neat appearance to the hat and at the same time prevent the perspiration from getting around the corner thereof to the hat body.

5 It is a further object of the present invention to provide a fabric head band or sweat band for hats and caps which will be yielding and flexible to conform with the shape of a head, yet which will not stretch and thereby lose the proper 10 head size and allow the hat to slide from the head of a user; that is, to provide a sweat band which will not stretch, but will maintain its original size at all times and thereby insure a snug fit upon the head of a wearer. This is especially desirable 15 in hats with sweat bands such as the present one made of fabric which is normally much more yielding than the sweat leathers ordinarily used in hats.

To this end the present invention provides a 20 band of unyielding material extending around the sweat band at the point where it engages the head and which would normally be subject to the greatest amount of stretch, capable of preventing the sweat band from stretching and 25 thereby maintaining the band in the originally formed size.

In hats it is desirable to have the sweat band serve as a retainer to cooperate with the hat body in keeping the crown lining in place. However, when the sweat band is not possessed of 30 strength, the weight of the fabric lining causes it to bend over and thereby spoil the appearance of either or both the sweat band and the crown lining.

35 It is an important object of the present invention to provide a fabric sweat band capable of properly supporting the crown lining between itself and the hat body and which will do this without bending or wrinkling even though it is made of light, flexible fabric in the main section.

40 Other objects, features, and advantages will appear hereinafter.

Referring now in detail to the drawing:

45 Figure 1 is a perspective view of the complete sweat band of the present invention.

Fig. 2 is a fragmentary and sectional view of one form of sweat band made in accordance with the present invention and applied to a hat which is shown fragmentarily.

50 Fig. 3 is a fragmentary sectional view similar to Fig. 2 but shows the composite sweat band made with an additional water-proofing or moisture impervious member thereon.

Fig. 4 is a fragmentary and sectional view of 55 a simplified form of the present invention.

Fig. 5 is a slightly modified form of the invention shown in Fig. 4.

Fig. 6 is a fragmentary view showing a modified connection between the head band and the back- 60 ing member.

A sweat band 10, shown in Fig. 3, is the form of the present invention now preferred, and accordingly is first described. It comprises a head band 11 of any kind of fabric. At present fabrics 65 made of synthetic fibres such as "Celanese", "Rayon", and the like are preferred. A soft yielding weave to the material is preferable, and may be provided to any desired degree in the now well known manner of making fabric materials.

70 The fabric head band 11 is laid upon and supported by a backing member 12, preferably by lapping margins 13 and 14 thereof over side edges 15 and 16 and by adhesively securing the margins to the outer side 17 of the backing member, as 75 by adhesive bands 23 and 24.

This backing member 12 is a particularly important part of the present invention and should therefore be particularly noted. It is preferably made of a felted, self-supporting material which is highly permeable or absorbent, to readily absorb the perspiration collected by and seeping through the fabric head band 11, and also sufficiently porous to readily evaporate the collected perspiration subsequently. While a blotting paper may be used for this purpose, other tougher 10 yet absorbent materials are preferred. At present a paper like composition of fibrous material known by the trade name of "Solka", and used regularly on the inner sole of shoes, has been found most satisfactory for the purpose. 15

However, it is desired not to limit the backing member 12 to any particular material, with the exception however that it is preferably absorbent, tough, and self supporting. The latter characteristic is particularly desirable since it serves the 20 important function of supporting and maintaining the superposed and soft fabric head band 11 in a raised or inverted position within a crown 21 of a hat 20 and prevents it from being pulled out of the crown when a user lifts the hat from his 25 head.

Further, by being self supporting, the backing member 12 may be provided with a flange 18 to prevent perspiration from reaching the brim 19 of a hat 20 and indirectly from reaching a crown 20 21 thereof.

It is within the purview of this invention to furnish the contemplated sweat bands either with or without the flange 18. Since the backing member 12 is self supporting it is capable of 35 maintaining and supporting the soft fabric head band 11 in a stretched position about the flange 18.

A waterproof coating 22 is preferably applied to the outer side 17 of the backing member 12, 40 as by a brush, spray, or any other of the now well known ways. The coating may be of rubber, of varnish, or similar material. Preferably the coating is of a consistency and thickness adapted to impart additional rigidity or otherwise improve the self supporting character of the backing member 12, yet sufficiently flexible to allow the band to conform with variously shaped heads without cracking. It also prevents the backing member 12 from stretching adversely. It serves 50 the important function of preventing perspiration from passing entirely through the backing member and thereby protects the adjacent hat 20 and usual outer hat band from being adversely subjected to an impregnation of perspiration. 55

By applying this coating prior to lapping the margins 13 and 14 over the edges 15 and 16, the coating may be used to secure the head band 11 thereto. However, to insure an even thickness and substantially impervious coating 22, separate 60 bands of adhesive 23 and 24 are used to secure the head band in place after the coating 22 has been dried on the backing member 12.

If preferred the head band 11 may be secured to the backing member 12 by a line of stitching 65 25 to the top edge 15, as shown in Fig. 6, and likewise to the bottom edge 16, thereby also imparting an ornamental effect to the edge of the band.

Although the backing strip 12 may be of a 70 woven material, it is preferably made of a pressed fibrous material since it may more easily be covered with a coating 22 and more certainly be rendered impervious.

The porosity of the backing member forwardly 75

of the coating 22 and the interstices between the fibres of the fabric 11, facilitate a rapid evaporation of accumulated perspiration from the band.

Prior to securing the margin 14 to the outer side though, a sizing strip 26, such as a closely woven cloth tape which is incapable of yielding or stretching, is also superposed upon the backing member 12. This strip serves the important function of preventing the more or less yielding 10 head band 11 and backing member 12 from stretching from the original fabricated head band size. It may be secured to the backing member 12 by the coating 22 or by the adhesive 24, preferably the latter, whereupon the outer side of 15 the strip, too, may be coated with adhesive 24' in order to receive and hold the outer extremity of the margin 14.

A waterproof barrier member 28 is also preferably provided on the composite sweat band 12, 20 of either oiled or rubberized silk, or other waterproof materials now used for like purposes in the back of sweat bands of leather and other materials. The use of a material having the trade-name of "Blossom", and generally consisting 25 of a silk or other fabric treated with "Glyptal" or glycerol-phthalate has been found most satisfactory since this material is very flexible, yet it is not affected by body acids, etc., found in perspiration, and consequently has a long life. It 30 may be secured to the composite band as by suitable bands of adhesive 29 and 30. When the barrier member 28 is provided, the waterproof coating 22 may be dispensed with. However, because of the extreme desirability of keeping perspiration from the hat, both are preferably embodied in the sweat band.

Thus it will be seen that the composite sweat band 10, of Fig. 3, comprises the head cloth 11, backing member 12, sizing strip 26 and the barrier member 28, preferably secured together in the manner hereinbefore described, although the sizing strip 26 may be superposed upon the margin 14 rather than underneath it and other minor changes made within the purview of the present 45 invention. After the various elements thereof are so secured together they are cut to the exact desired length (viz., to equal the circumference of the desired sweat band size) and then secured together at adjoining ends 31 and 32 as by a line 50 of straight stitching 33, or zig-zag stitching 34, as shown in Fig. 2.

Thereafter the completed sweat band may be secured to the hat in any of the now well known ways, for example, as by edge stitching 35 shown 55 in Fig. 4. After it is so secured in place it serves to advantageously support a crown lining 36 within the hat 20. The backing member is sufficiently self supporting to keep the lining in place and to prevent the fabric head band 11 from 60 curling out of the crown as the user removes the hat from his head. The fabric member 11 and/or the backing member effectively absorb and evaporate perspiration, while the coating 22 and/or the barrier member 28 effectively prevent 65 perspiration from reaching the hat 20 or the usual outer hat band.

Figure 2 shows a modified form of composite sweat band 10A which is the same as the sweat band 10 just described in detail, excepting for the 70 omission of the barrier member 28, and consequent detailed description thereof again would be superfluous. In many instances and in temperate climates, the coating 22 alone has proven sufficient to prevent perspiration from reaching the 75 hat 20. In the hotter climates where perspiring

is more prevalent the use of the barrier member 28 on the band 10 is more satisfactory and preferred.

When an unelastic "Glyptal" rather than an elastic rubber coating 22 is applied to the outer side of the backing member 12, the sizing strip 26 may also be dispensed with, as shown in Fig. 1, since the coating serves in a considerable measure to prevent the sweat band from stretching. However, the unyielding sizing member 26 makes a 10 more positive and effective sweat band.

Figure 4 shows a sweat band 10B which is a further modified form of the present invention wherein the barrier member 28 alone serves to support and maintain the fabric head band 11 in 15 the inverted position within the hat, and to prevent the passage of perspiration to the hat. Although this barrier band may be treated with rubber to render it impervious, it has been found that rubber has a short life, does not resist body 20 acids, and is somewhat elastic.

A fabric member treated with synthetic resin, such as "Glyptal" is inert to body acids, has a long life, and is not elastic. Consequently it has been found much more satisfactory for this purpose. Since it can be made of any desired consistency and strength, it serves effectively to support the fabric head band 11. In this form, in order to achieve the head band supporting characteristics, the barrier strip 28 is made much 30 thicker than when it is applied to both the head band 11 and backing member 12.

Fig. 5 shows a sweat band 10C which is like the sweat band 10B, just described in detail, in nearly every particular except that two thin 35 rather than one thick barrier strip 28 is provided. As with the other forms of the invention the barrier strips and the fabric head band may be secured together by an adhesive or by marginal lines of stitching 25. The double thickness 40 of thin barrier strips has the advantage of greater flexibility than the single thick barrier strip of the sweat band 10B so that it will better conform with irregularities of one's head and at the same time will serve to support the head band 12 45 in an upright and wrinkle-proof condition to the same degree as the one thick barrier member 28 of the band 12B.

In the sweat bands 10B and 10C the barrier strip may be provided with a supplemental coating 22, of rubber varnish or the like, but preferably of glycerol-phthalate.

Although the present invention has been described primarily as applied to a hat, it is equally applicable for use with caps, as will be readily understood by those in this art.

Other variations and modifications may be made within the scope of this invention and portions of the improvements may be used without others.

Having thus described the present invention, what is claimed as new and for which it is desired to obtain Letters Patent is:

1. A composite sweat band for hats comprising a fabric head band; an absorbent backing member, more rigid than the head band, adapted to support the fabric head band and prevent it from wrinkling; a sizing strip of substantially unyielding material, adapted to prevent the head band and backing member from stretching; a waterproof barrier member encircling said absorbent backing member; and means for securing said fabric head band, absorbent backing member, sizing strip, and waterproof barrier member together.

2. A composite sweat band for hats comprising a fabric head band; an absorbent backing member, more rigid than the head band, adapted to support the fabric head band and prevent it from wrinkling; a waterproof coating on said absorbent backing member; a sizing strip of substantially unyielding material, adapted to prevent the head band and backing member from stretching; a waterproof barrier member encircling said absorbent backing member; and means for securing said fabric head band, absorbent backing member, sizing strip, and waterproof barrier member together.
3. A composite sweat band for hats comprising a fabric head band; a highly absorbent backing member, more rigid than the head band, adapted to alone support the fabric head band and prevent it from wrinkling; a sizing strip of substantially unyielding textile material, adapted to prevent the head band and backing member from stretching; and means for securing said fabric head band, backing member, and sizing strip together.
4. A composite sweat band for hats comprising a fabric head band; an absorbent backing member of self-supporting material, more rigid than the fabric head band, adapted to alone support the fabric head band and to prevent it from wrinkling; a waterproof coating on said backing member on the side away from said fabric head band; means for securing said fabric head band to said backing member; and an outwardly extending peripheral flange on said backing member at the lower edge thereof adapted to alone impart and sustain a flange-like shape to the fabric head band.
5. A composite sweat band for hats comprising a fabric head band; an absorbent backing member of pressed fibrous material, more rigid than the fabric head band, adapted to alone support the fabric head band and to prevent it from wrinkling; a waterproof coating on said backing member on the side away from said fabric head band; and means for securing said fabric head band to said backing member.
6. A composite sweat band for hats comprising a highly absorbent backing member of self supporting material having top and bottom edges and an outer side; a fabric head band supported by said backing member and having top and bottom margins overlapping the top and bottom edges and the outer side thereof; a sizing strip of substantially unyielding material encompassing said head band member and said backing member to prevent stretching of said members; and a waterproof barrier member forming an outer face for the sweat band.
7. A composite sweat band for hats comprising a fabric head band; a highly absorbent backing member of felted material for absorbing moisture from the head band more rigid than the fabric head band, adapted to alone support the fabric head band and to prevent it from wrinkling; a sizing strip of substantially unyielding textile material; and means for securing said fabric head band to said absorbent backing member and sizing strip.

JOHN CAVANAGH.
